UNITED STATES PATENT OFFICE.

HANS BRUNNER, OF OUDER AMSTEL, NETHERLANDS.

PLUG COCK.

Application filed July 27, 1920. Serial No. 400,520.

To all whom it may concern:

Be it known that I, HANS BRUNNER, citizen of Switzerland, residing at Ouder Amstel, Weespervaat 184c, Netherlands, have invented certain new and useful Improvements in Plug Cocks, of which the following is a specification.

This invention relates to an adjustable plug valve for steam, water and gas under pressure and has for its object to provide improved means for permitting the renewal of the packing while the valve is under pressure and for preventing jamming of the plug in the valve casing and leaking of the packing. The main disadvantages of the valves hitherto designed and used are, that when a renewal of the packing becomes necessary the pressure to which the valve may be exposed must be removed from the valve and its piping-system.

Besides if the packing-gland is screwed or pressed too hard on the packing, the plug will be driven too tightly into the casing, which may cause jamming and possible damaging of the plug when turning it.

With the above object in view the invention consists in the details of construction and in the arrangement and combination of parts as will be hereinafter fully described and specifically claimed.

In describing the invention in detail reference will be had to the accompanying drawings wherein like characters of reference denote corresponding parts and in which:

Fig. 1 is a vertical sectional view of one form of the invention.

Fig. 2 is a view partly in plan and partly in horizontal section on line A—B, Fig. 1.

Fig. 3 is a side elevation of the plug;

Fig. 4 is a top view thereof;

Fig. 5 is a side elevation of a sleeve or bushing which is employed;

Fig. 6 is a top view thereof;

Fig. 7 is a vertical section showing a modification;

Fig. 8 is a top view thereof;

Fig. 9 is a vertical section of a further modification;

Fig. 10 is a top view thereof;

Fig. 11 is a side elevation of the plug represented in Fig. 9.

Fig. 12 is a top view thereof.

In Figs. 1, 2, 3, 4, 5, and 6, 1 is the valve casing, 18 the plug valve and 13 a caplike

sleeve or bushing, adapted to be fitted over the stem 6 of the valve 18 and fastened thereto by means of a key 14.

The sleeve 13 is provided at its lower end with a flange, which rests on an annular shoulder or seat 2 formed in the upper portion of the valve casing a slight distance above the valve, said flange being encircled by a ring 12, also resting on the seat 2, and being held in place on said seat by an externally screw-threaded ring 3 which is screwed into the upper part of the casing on top of the ring 12; the height and the diameter of both rings being such that the flange may be easily turned in the space formed by said rings. The cap 15 of the sleeve 13 is made square to permit the operating lever or handle to be fitted thereon, and is formed with a threaded bore, through which passes the screw 9, the latter having a head 8 which fits into a slot 7 in the top of the stem 6 and is turnable therein. The bolt 9 is provided with a nut 11 and a square end 10 for fixing and adjusting the position of the valve.

4 is the gland, which fits around the sleeve 13. The space between the gland 4 and the ring 3 serves for the packing.

With the arrangement hereinbefore described it is obvious that after having brought the sleeve 13 and the rings 12 and 3 into their proper position, and having fixed and adjusted the position of the plug 18 in the casing 1 by turning the screw 9 and screwing the nut 11 against the cap 15 of the sleeve 13, the packing may at any time be taken out or put into the space between the ring 3 and the gland 4, as this space is situated outside the sphere of action of the pressure. Besides when screwing down the gland 4 against the packing, the pressure will be taken up by the ring 3, so that this pressure cannot be transmitted to the plug 18 and will not cause the plug to become jammed.

As the described arrangement allows a very accurate adjustment of the plug, and as the position of said plug, when once adjusted, cannot be altered, the chance of leaking is a very small one, even in case of a renewal of the packing, when the packing is liable to contract and leak. Figs. 7 and 8 show a modification of the arrangement for adjusting and fixing the position of the plug.

Instead of utilizing the cap 15, the screw 9 and the key 14 for attaching the sleeve

to the valve stem 6, the said stem 6 is extended beyond the sleeve 13 and its upper part is provided with screw-threads 16 for screwing it into the sleeve, the upper part 5 of which is also threaded. The top part of the stem is made square to enable the attachment of a handle or lever for adjusting the position of the plug 18, while the nut 11 is used for maintaining this position after adjustment; for turning the plug 18 in the casing 1, the sleeve may be provided with recesses 17, adapted to engage a suitable instrument.

The arrangements hereinbefore described 15 may be used for valves which are only accessible from the top; in case they are also accessible from the bottom, the construction shown in Figs. 9, 10, 11 and 12 is preferably used, as being considerably simpler 20 and cheaper to construct; in such case, the sleeve 13, the key 14 and the screw-threaded extension 16 may be omitted.

Instead of the upper end of the valve stem being provided with the slot 7, this slot is 25 cut in the bottom of the plug itself and the screw 9 fits into the bottom of the plug; the position of its nut 11 being as shown in Fig. 9.

The various parts as disclosed in Figs. 30 9, 10, 11 and 12 are assembled by first placing the screw bolt 9 in the slot 7 of valve 18 and then inserting these two elements

into the casing 1 whereby the square end 10 will pass through the bore of the casing until the threads of the bolt reach the 35 threads of the bore. The plug is then forced into the casing and by means of the bolt 9 and the lock nut 11 secured in place. The parts 3, 4 and 5 are now inserted which completes the assembly.

Having now particularly described and ascertained the nature of my said invention and in what manner the same is to be performed I declare that what I claim is:

A valve structure comprising a casing 45 having a fixed bottom provided with a threaded bore and an inlet and an outlet for fluid; a tapered plug valve rotatably mounted in the casing and provided at the lower end with a slot; a screw bolt rotatable 50 in and disconnectable from said slot for longitudinally adjusting and holding the valve, said screw bolt being threaded directly into the fixed bottom of the casing and having at the lower end a square portion which is longer than the threaded bore in said bottom and passes without turning through and projects outwardly through the threaded bore in said casing; and a lock nut 55 on said screw bolt for securing said screw bolt against longitudinal movement.

In testimony whereof I affix my signature.

HANS BRUNNER.
